UNITED STATES PATENT OFFICE.

CHARLES L. BUCKINGHAM, OF NEW YORK, AND EMIL GERMANN, OF BROOKLYN, NEW YORK; SAID GERMANN ASSIGNOR TO SAID BUCKINGHAM.

TELEGRAPHY.

No. 826,472.

Specification of Letters Patent.

Patented July 17, 1906.

Original application filed November 2, 1899, Serial No. 735,623. Divided and this application filed December 7, 1901. Serial No. 85,028.

To all whom it may concern:

Be it known that we, CHARLES L. BUCKINGHAM, of the city and county of New York, and EMIL GERMANN, of Brooklyn, Kings county, State of New York, citizens of the United States of America, have made certain new and useful Improvements in Telegraphy, of which the following is a specification.

Messages are prepared in sections for transmission by the Wheatstone transmitter or other suitable apparatus and are reproduced by a page-printer, as in United States Patent No. 579,634, March 30, 1897, the several perforated sections of a message being separated by divisional spaces whereby Morse or other signals may be transmitted while such divisional spaces are passing through the automatic transmitter.

The present case is a division of our application, Serial No. 735,623, filed November 2, 1899, upon which patent No. 765,456, July 19, 1904, was granted, Figures 18, 19, 16, 17, 12, 13, 14, 15 of such original application having been herein reproduced as Figs. 1 to 8, inclusive.

Fig. 1 shows a duplex telegraph system adapted to the Wheatstone service and provided with special devices whereby in the operation of our printer system one side is made practically independent of the other. Fig. 2 is a skeleton view of the operative parts of a Wheatstone transmitter and is here presented to show in detail some of the parts that are not represented in Fig. 1. Fig. 3 represents a line-mark which is conspicuous and distinctive in appearance to show in the tape the termination of one line at its left and the commencement of a new line of the message to be reproduced upon the printer at the right. Fig. 4 shows a long space, the preferred form, between the sections or main divisions of a message. Fig. 5 is a diagram showing a line-mark or a group of perforations separating two lines of a message which is to be reproduced in page form by our page-printing telegraph. This is an alternative form which is here shown chiefly to indicate the advantages of the line-mark shown in Fig. 3. Fig. 6 is a diagram showing three repetitions of the line-mark group represented in Fig. 5. Fig. 7 shows three repetitions of the line-mark group of Figs. 5 and 6, but

with the spaces ending the groups omitted, this representing an erasure, a rub-out, or a divisional space for separating the main sections of a message. Fig. 8 shows the letters "a" "b" "c" of the printer code on each side of an erasure, rub-out, or divisional space. If the perforating operator were to make an error in any part of the message, the section of solid perforations here shown might be employed to cover the error, and at its end to the right the message might be resumed. This series of perforations, however, may also be employed to separate the main sections of a message. The sectional spaces of Fig. 4, however, is the preferred form, and Fig. 8 is shown only for the purpose of illustrating the advantages of the plan shown in Fig. 4.

Ordinarily a message to be reproduced by our page-printing telegraph is prepared in four main sections, the first of which contains the office-record of the message, the next the address of the person to whom the message is sent, the next the body of the message, and the next the signature. The divisional spaces between the four sections of a message might consist of a solid series of dot-holes in the tape, as shown in Figs. 7 and 8. In this case a long series of dot pulses would be sent over the line while the dividing-section was running through the Wheatstone transmitter; but the printer would remain unaffected by them, and during such time the feed-wheel of the printer could be disengaged from and reengaged with the escapement-pallets of the feed-wheel to bring the paper sheet upon which the message is printed to an initial position for the commencement of a new message. This plan has proved successful in practice; but to leave the section-spaces a plain blank, as in Fig. 4, is preferable for many reasons. If it were necessary to punch seven or eight pairs of holes at each depression of a key of the perforating-machine, the resistance to the operation of the key would be far greater than the depression of a key, which was intended only to operate the feeding device of the perforator by which the blank space of Fig. 4 is produced. Obviously for many reasons the divisional section of the tape may be produced as a blank section much more ex-

peditiously and conveniently than by filling said section with a solid series of perforations, as shown in Fig. 8; but aside from the many advantages in the production of a blank space as compared with a long series of perforations there is one of far greater importance: By employing a blank between the message-sections we are able to more nearly make one side of a duplex practically independent of the other when sending printer messages in opposite directions on a wire.

In our ordinary duplex if a receiving operator breaks back to the distant transmitting end to question the transmitting operator at that end the work of the other side or of the other transmitter and receiver is put in confusion and must be suspended. In other words, if the receiver on one side of a duplex finds it necessary to question his transmitting correspondent the two persons on the other side must wait. In our system, however, a receiving operator may call or signal to his sending operator whenever a blank space of the tape is passing through the Wheatstone transmitter. For all practical purposes a receiving operator is able to send signals that are adequate for the purpose by merely making three Morse dots—the letter "s"—when he sees a blank between sections of a message passing through the Wheatstone transmitter at his own station. If a swing on the wire (meaning that the wire momentarily touched another wire) has resulted in mutilating a message, the receiving operator merely sends a Morse letter "s" to the transmitting end under the conditions above stated, which means that the transmitting operator should rerun his tape. If, however, the fault were repeated during the rerun, the tape would be examined, and if found imperfect the message would be re-perforated. By this means a receiving operator in New York may give all necessary signals to his transmitting correspondent in Chicago without in any manner interfering with the message which at the time New York is sending to Chicago.

We will now describe the peculiar arrangement of apparatus by which this result is accomplished and the telegraph system as a whole, by which the blank spaces in the tape are made available to render one side of the duplex independent of the other.

If the four sections of a message were separated by a series of dot perforations, as shown in Fig. 8, a series of dot pulses would be transmitted over the line by the Wheatstone transmitter while such part of the tape was passing through the machine. These pulses would not interfere with the printer at the distant station; but their presence would prevent the transmission of such Morse signals as it might be necessary to send for the purposes already described; but if the sections

were separated by blank portions of tape a Morse letter or letters could be transmitted during the passage of such parts through the transmitter by a receiving operator in New York without interfering with a message then being sent from New York to Chicago. To accomplish this result, we do not employ additional battery or change the repeating apparatus, nor do we do more in changing the receiving and transmitting apparatus of the system than to place an additional hand-switch on the Wheatstone transmitter at each end of the line. We add to each Wheatstone transmitter a switch, as shown in Fig. 1, by which we are able to send Morse signals when the pulse-reverser of the transmitter is momentarily arrested in one of its two operative positions. Each transmitter is provided with the same Morse key that is usually employed with a Wheatstone set for breaking purposes, and by means of such key while the blank strip is passing through the machine the Wheatstone battery may be reversed to signal the opposite station. It would not, however, answer to reverse the battery once or even twice, inasmuch as any less than three reversals would interfere with the operation of the printer at the distant station—that is to say, the printer as shown in the patents of Buckingham and Germann, No. 544,347, August 13, 1895, and No. 579,634, March 30, 1897, is so constructed that three reversals or any multiple of three would not interfere with whatever message it might be receiving; but as the printer is constructed other numbers would cause confusion.

Referring to Fig. 1, two stations are shown which are joined by a main line 135, and at each is a polarized differential relay, preferably of the Wheatstone type, and a Wheatstone transmitter, the operative parts of which are outlined in Fig. 2. The contact-bars 103 109, which are simultaneously actuated by a handle 101, which is pivoted to base-plate 100, are shown in their normal position. In this position with pulse-reversing bar or arm 118 held against stop 112, as shown, a circuit is formed from earth Gr to the middle of battery 138, thence to the left by contact 126, armature-bar 127, wire 111, stop 112, arm 118, wires 116 117, and through the differential relay by way of the main and artificial lines. By this means a negative pulse is sent over main line 135 to the distant station. When, however, pulse-reversing arm 118 is moved into contact with 113 and away from 112, the circuit from Gr is formed through the right half of battery 138, wire 123 121, switch-bar 108, wire 114, contact 113, arm 118, wires 116 117 through the differential relay, the main line, and thence to the distant station, and in this position of 118 a positive pulse is transmitted to the main line. It is thus seen that the positive

and negative currents are alternately sent to the main line with the oscillations of 118. If, however, 118 were momentarily held against 112, as would be the case while a blank piece 5 of tape was passing through the transmitter, reversals of current could still be sent over the wire by working the Morse key 130. When the key 130 is open, a negative current must flow to line, as has already been described; but upon depressing said key magnet 129 would attract armature 127 to contact 125 and thus form a circuit from the positive pole of battery 138 by wire 122, armature-lever 127, wire 111, and, as before, to line—that is to say, by depressing the Morse 15 key a positive pulse is sent to line in place of the negative which was flowing when the key was in its upper position. It is thus apparent that a polarized relay may be operated 20 at a distant station by a Morse operator while a blank tape is running through the Wheatstone transmitter at the home station, thereby giving to the system for breaking purposes substantially the capacity of a 25 quadruplex.

When handle 101 of the switch is moved to the right, thereby placing 104 in contact with 105 and 108 in contact with 107, the Wheatstone transmitter will be disconnected; but at 30 the same time communication by Morse is established.

With the switch in one position, the system is adapted for Morse, while in the other, as shown in Fig. 1, it is adapted for regular 35 Wheatstone, and at the same time for Morse, while the contacts of the Wheatstone transmitter are so held as to transmit to line a continuous negative current. Of course the connection might be so changed as to allow 40 Morse to be sent during a positive prolongation of current; but as the Wheatstone transmitter usually sends a negative current during the passage through it of a blank piece of tape we have adopted the arrangement here 45 shown. It is thus seen that our preferred plan contemplates as an essential condition the transmission of a continuous current of one polarity during the time that a part of the tape between sections of a message is passing 50 through the transmitter. Obviously this is most conveniently effected by leaving the dividing portions blank; but the same result might be accomplished if dot-holes were perforated in one side of the strip. More generally, however, our invention contemplates the division of a message or other matter to be transmitted into sections with a blank, dot, or other spacing between sections 55 of sufficient length that as such spaces are passing through an automatic transmitter at one station Morse signals from the same station may be sent without interfering with the other side of the duplex.

If the divisional space were a series of dots, 60 as in Fig. 8, a signal could be sent by depress-

ing key 130 once. In this case during the depression of key 130, contact having been broken between 126 and 127, a series of short positive pulses would be sent to line, which would act upon the distant polar relay, as 70 would a continuous positive current, to give one signal. These short positive pulses would not interfere with the receiving printer at the distant end; but as there would be only one stroke of the relay the signal would 75 not be as distinctive as if there were one or more letters like the Morse "s." Other disadvantages of this plan in comparison with that where blank tape spaces are used have been sufficiently noted.

What we claim, and desire to secure by Letters Patent, is—

1. A message-tape in which messages are prepared for transmission by the Wheatstone transmitter or other equivalent apparatus, and for reproduction by a page-printer, each of said messages being represented by several sections of perforations, said sections being separated by blank spaces, as herein shown and described, whereby Morse or other signals 80 may be transmitted while the spaces between said sections are passing through said transmitter.

2. In a message-tape, the combination of groups of perforations representing, respectively, several sections of a message, and divisional spacings between said sections, as 95 and for the purpose set forth.

3. A tape having messages prepared therein in sections for transmission by the Wheatstone transmitter or other equivalent apparatus, and for reproduction by a page printer, the recorded messages consisting in separate parts of perforations with blank spaces between said sections, as and for the purpose 100 set forth.

4. In a message-tape, the combination of groups of perforations representing, respectively, several sections of a message and intermediate blank portions of tape between said 105 sections.

5. In a duplex telegraph, the combination of an automatic transmitter, a manual transmitter and a switch at each station, and a message tape for operating said transmitter 115 in which several sections of the message are separated by divisional spaces

6. In a duplex telegraph, the combination of a Wheatstone transmitter having a pulse-reverser, a message-tape having blank spaces 120 between sections of the message for controlling the action of said pulse-reverser and for continuously holding said pulse-reverser in one position during the passage of blank parts of the tape through said transmitter, and a 125 Morse key by which signals may be sent at such times.

7. In a duplex telegraph, the combination of an automatic transmitter having a pulse-reverser, a message-tape having divisional 130

spaces between sections of the message, and a Morse key by which signals may be sent as said divisional spaces pass through said transmitter.

5 8. In a duplex telegraph, the combination of a Wheatstone transmitter, a Morse key, a message-tape having blank spaces, a main line and battery, and a switch whereby the Morse key may alone be placed in operative relation with the line, or whereby said key may be in position to send signals while blank

parts of the tape are passing through the Wheatstone transmitter.

In testimony whereof we have signed our names to this specification in the presence of 15 two subscribing witnesses.

CHARLES L. BUCKINGHAM.
EMIL GERMANN.
